TWO-UNIT WELTING

William C. Vizard, Brockton, Mass., assignor to
 Barbour Welting Company, Brockton, Mass., a
 copartnership

Application March 26, 1949, Serial No. 83,660

4 Claims. (Cl. 36—78)

1
 This invention relates to two-unit welting of the heavy edge type disclosed in my prior Patents No. 2,414,249, dated January 14, 1947, and No. 2,427,984, dated September 23, 1947.

The shoe welting produced in accordance with the disclosures of my said patents comprises a base portion and a top portion cemented and molded together, the top portion having a grain surface constituting the welt extension and a grain lip extending along its inner edge and folded downwardly and cemented against an inclined shoulder of the top unit and against the inner edge of the bottom unit.

The principal purpose of the present invention is to provide a welt of the aforesaid type in which the grain lip is omitted, thereby simplifying and expediting the welt making process, by forming a shoulder along the inner edge of the top unit, at the upper portion thereof, the shoulder being curved or inclined inwardly to provide a longitudinal recess or groove which permits the inseam lip of the two-unit welting to flex freely when sewed into the shoe and which receives the inseam stitch.

A further object of the invention is to provide a two-unit welting having a top section provided with a flesh lip extending inwardly beyond the aforesaid shoulder and cemented to the top of the inner edge of the bottom section or unit, to provide an inseam edge which has adequate thickness but which is more flexible than the inseam edge of the grain surfaced sewing edge shown in my prior patents.

The shoulder of the top unit is thus composed partly of grain leather and partly of flesh leather, and this shoulder fits snugly against the upper of the shoe made with the improved welting. When the shoulder is rounded, in cross section, as preferred, it hugs more closely against the shoe upper and serves to prevent grinning of the seam, or chafing of the upper during the shoemaking operations.

A recommended embodiment of the invention, showing a preferred method of making the improved welting, is illustrated in the accompanying drawings, but it will be understood that the manufacturing process and the structural details of the welt product herein illustrated and described may be varied to suit particular requirements, without departing from the essence of this invention, as defined in the appended claims.

In the drawings,

Fig. 1 is a perspective view of a leather fillet formed with longitudinal cuts designed to produce the two units of the heavy edge welting;

2
 Fig. 2 is a view similar to Fig. 1, showing the fillet partially separated to indicate the formation of the respective units;

Fig. 3 is a perspective view of the assembled, 5 two-unit welting, and also illustrating the removal of a string-like piece from the inner edge of the base or bottom unit, and the formation of the inseam groove in said base; and

Fig. 4 is a fragmentary section through the toe 10 portion of a shoe made with the welt of Fig. 3.

In the particular form chosen for the purpose of illustration, the improved welt is made from a leather fillet 11 having a width of $\frac{1}{8}$ " and a thickness of $\frac{1}{16}$ ", the grain surface of the fillet being uppermost in Figs. 1 and 2. The fillet is divided longitudinally by a knife which separates the fillet into two strands 12 and 13, by a transverse cut extending through the grain surface at 14 and curving at 15 into a part of the flesh portion of the fillet, then extending at 16, at a slight downward inclination to the plane of the fillet, and finally terminating in a downward incision 17 to the bottom of the fillet, as shown in Fig. 1.

This irregular longitudinal cut produces a top 25 unit 13 having a rounded shoulder 18 extending along the inner edge of its upper portion, a groove or recess 19 extending along the bottom of said shoulder, and a flesh lip or flange 20 projecting laterally beyond said shoulder, as shown in Fig. 2; and a base unit 12 having a grain flange 21 extending along one edge thereof, the flange 21 being of reduced thickness and having a recessed edge 22 formed by the cut 15, as also shown in Fig. 2.

30 In assembling the two welt strands or units, the flesh side of the top unit 13 is applied to the grain side of the base unit 12, with the flesh flange 20 and grain flange 21 in substantial registration, and the two parts are firmly cemented together, as shown in Fig. 3. A small flesh ribbon or rand 23 is preferably cut from the under edge of the flange 21, and the inseam groove 24 is formed behind said flange, either before or after the parts are assembled. The two-unit welting 40 may then be molded to desired shape for the shoe manufacturer.

The improved welt provides a two-unit welting strip approximately $\frac{1}{8}$ " wide, and is built into the shoe in a conventional manner, the inseam stitch 25 passing through the bottom groove 24 and the groove 19 of the top unit, as shown in Fig. 4, with the shoulder 18 fitting closely against the upper, beneath the feather of the insole. Inasmuch as the flange 20 of the top unit is of flesh stock, the sewing edge formed by said ele-

ments may be flexed freely, and the groove 19 provides a convenient hinge on which the two-ply edge may be bent downwardly during the in-seaming and welt beating operations. The reduced thickness of the flange 12 of the base unit assists in affording such flexibility.

Although the flange 21 has an upper surface of grain leather, when the parts are assembled, as above described, it will be evident that the base unit 12 may be reversed in position, so that the flesh side of the top unit is applied and cemented to the flesh side of the bottom unit, the inseam groove being then cut in the exposed grain side of the base unit. In such case, the flesh flange 20 of the top unit would be bent downwardly onto the stepped flange 21 of the base unit in assembling the two strands; and such modification of the welt herein described is contemplated as within the scope of this invention which relates primarily to two-unit weltling in which the top unit has a receding shoulder inclined, and preferably curved, downwardly and rearwardly from its grain surface, to form a longitudinal groove between the shoulder and the flesh flange which projects laterally beyond the shoulder and overlies a reduced flange of the bottom unit.

I claim:

1. Two-unit weltling comprising a base unit having a flange of reduced thickness along its inner edge, and a top unit having a grain surface, a longitudinal shoulder extending downwardly from said surface intermediate the edges of said unit, and a longitudinal flesh flange extending laterally beyond said shoulder, the flesh side of the top unit being cemented to one side of the base unit with said flanges in substantial registration, said shoulder receding from the grain surface into the flesh portion of the top unit, and said top unit having a longitudinal groove between said receding shoulder and said flesh flange.

2. Two-unit weltling comprising a base unit having a flange of reduced thickness along its

inner edge, and a top unit having a grain surface, a longitudinal shoulder extending downwardly from said surface intermediate the edges of said unit, and a longitudinal flesh flange extending laterally beyond said shoulder, the flesh side of the top unit being cemented to one side of the base unit with said flanges in substantial registration, said shoulder inclining downwardly and rearwardly from the grain surface and into the flesh portion of the top unit, and said top unit having a longitudinal groove between said shoulder and said flesh flange.

3. Two-unit weltling comprising a base unit having a flange of reduced thickness along its inner edge, and a top unit having a grain surface, a longitudinal shoulder extending downwardly from said surface intermediate the edges of said unit, and a longitudinal flesh flange extending laterally beyond said shoulder, the flesh side of the top unit being cemented to one side of the base unit with said flanges in substantial registration, said shoulder inclining downwardly and rearwardly from the grain surface and into the flesh portion of the top unit, and said top unit having a longitudinal groove between said shoulder and said flesh flange.

4. Two-unit weltling comprising a base unit having a grain side and a grain flange of reduced thickness along its inner edge, and a top unit having a grain side, a rounded longitudinal shoulder inclining downwardly and rearwardly from its grain side intermediate the edges of said unit, a longitudinal flesh flange extending laterally beyond said shoulder as a continuation of the flesh side of said unit, and a longitudinal groove between said shoulder and flange, the flesh side of the top unit being cemented to the grain side of the base unit with said flanges in substantial registration.
